VAULT DOOR STOPPER

Filed Nov. 25, 1927

Patented Apr. 2, 1929.

1,707,482

UNITED STATES PATENT OFFICE.

ALFRED H. JOHNSEN, OF WHITING, INDIANA.

VAULT-DOOR STOPPER.

Application filed November 25, 1927. Serial No. 235,408.

This invention relates to means for preventing a door from being fully closed and locked, and is especially intended for bank vault doors for making it impossible to close and lock the same, in case of a robbery during banking hours, so that the bank employees cannot be locked in the vault.

The bank vaults in common use are provided with a door frame having a door-jamb adapted to receive snugly therein a vault door for closing and locking the opening in the door frame. The vault door is generally provided with a system of bolts which are adapted to slide out of and into the edges of the door, to engage and disengage the interior face of the door frame in locking and unlocking the door. The interior face of the door frame is usually provided with a series of small reinforcing plates or 20 lugs securely attached to the door frame near the opening therein and at points where the ends of the projected bolts engage with the interior face of the door frame.

It is the main object of this invention to 25 provide an attachment or device which will when associated with a vault door frame of the character described prevent the complete closing and locking of the vault door.

Another object of this invention is to 30 provide an attachment or device which is adapted to be detachably connected with a vault door frame of the character described whereby the complete closing and locking of the vault door is made impossible.

35 A further object of this invention is to provide an attachment or device adapted to be detachably held on a projection on the interior of the vault for preventing the moving of the vault door to its fully closed position.

40 A still further object of this invention is to provide an attachment or device which will when placed in operative position on a vault door frame of the character described prevent a full closure of the door.

45 A still further object of this invention is to provide an attachment or device adapted to be detachably secured to a portion of a vault door frame of the character described 50 for preventing the complete closing and locking of the vault door, and which is so positioned on said door frame as not to be noticeable thereon, whereby the possibility of an unauthorized removal of said device 55 is avoided.

A still further object of this invention is

to provide an attachment or device of spring metal or the like adapted to be sprung over and held on a projection on a vault door frame of the character described for preventing the full closing and locking of the vault door, the said device being so constructed and positioned on said vault door frame as to avoid the possibility of its unauthorized removal.

60 A still further object of this invention is to provide an attachment or device adapted to be detachably held at one or several points along the inner edge of a vault door frame of the character described, for preventing the complete closing of the vault door, the said attachment or device being so made and positioned on said door frame as not to be noticeable thereon, whereby the possibility of its unauthorized removal may be avoided.

65 A still further object of this invention is to provide an attachment or device of substantially resilient material comprising a body portion adapted to be snapped over and held on a projection on the interior of a vault door frame of the character described, and having a portion adapted for engagement with the door-jamb, and being so made and positioned on the frame as not to be noticeable thereon, whereby the possibility of its unauthorized removal will be avoided.

70 A still further object of the invention is to provide an attachment of the character described for preventing the closing of a vault door or the like, and which will be cheap and easy to manufacture, simple in operation, quickly and easily snapped into operative position, readily removable by one authorized to do so from engaging operative 75 position, and efficient in carrying out the purpose for which it is designed.

75 With the foregoing and other objects in view, which will appear as the description proceeds, this invention consists in the design and construction of my attachment or device whereby the objects contemplated are attained, as hereinafter more fully set forth, pointed out in the appended claims, and illustrated in the accompanying drawings, 80 which form a part of this application, and in which:

85 Figure 1, is a view in elevation showing a portion of a vault door frame, a vault door hinged thereon, and the device embodying 90 my invention shown on the door frame in operative position;

Figure 2, is a view in section taken on the line 2—2 of Fig. 1, showing the device of my invention in operative position on the door frame;

5 Figure 3, is a view in elevation of the interior of a vault door frame of the character described showing the reinforcing plates or lugs thereon; and

10 Figure 4, is a view in perspective of my device embodying the invention.

In order that my invention may be more fully understood, I have illustrated in the accompanying drawings, which are referred to herein and form a part hereof, one embodiment of the invention as applied to a bank vault, the same serving to illustrate by way of example the principles of the invention.

Referring to the specific embodiment of the invention illustrated by way of example 20 in the drawings, 1, represents a vault of well known construction of the kind used in banks or the like, the said vault having a rectangular opening therein in which is adapted to fit snugly a vault door frame 2, to which is 25 hinged by means of the hinges 3, a vault door 4, of well known construction. The vault door 4, is of considerable thickness and is adapted to fit snugly in the door frame 2, for closing the opening therein.

30 The vault door 4, is provided on the inner face thereof with a system of bolts, said bolts being operable to slide out of and into the edges of the door, to engage and disengage the inner face of the door frame, in locking and unlocking the door. In the specific 35 construction of vault door illustrated in the drawings, the door 4, is provided with a bolt frame 5, on the inner face thereof, and interior ribs 6, through which a series of bolts

40 7, pass in sliding out of and into the edges of the door 4, the said bolts being connected together by means of plates or the like, whereby a single operating mechanism may be operated to actuate all of the bolts simultaneously.

45 The operating mechanism for the bolts may comprise a lock 8, which is connected to one end of a vertically disposed bar or rod 9, having an elongated slot therein for permitting vertical movement. The rod or bar 9, has provided thereon on each side thereof a series of teeth adapted to engage with pinion wheels 10, to rotate the same, said wheels being in engagement with teeth provided on one side of horizontally disposed rods or bars 11, for reciprocating the same.

50 The rod or bar 9, is adapted to engage the plate connecting the bolts in the top edge of the door for actuating the same, and the rods or bars 11, are connected with the bolts in the side edges of the door and are adapted to actuate these bolts. A construction similar to the one described above is also provided in the lower portion of the door, not shown. It will thus be readily understood that by manipulating the locking means 8, the bolts 7

will be actuated to be simultaneously projected or withdrawn. The specific construction of the vault door with its bolt mechanism forms no part of the present invention and need not therefore be described more in detail.

When the door is in closed and locked position, the projecting ends of the bolts 7, are adapted to engage with or rest against a portion of the interior face of the door frame, 75 said portion being provided with a reinforcing plate or lug 12, rigidly secured to the said door frame on the inner face thereof adjacent the opening therein as shown in the drawings. The plates 12, may be provided 80 with a slightly depressed central portion for receiving the projecting end of the bolt. The above construction is well known in the art and since it forms no part of the present invention it is not thought necessary to describe 85 the same more in detail.

In connection with the vault door construction above described, I provide means for preventing the closing and locking of the door. The said means comprising a clasp- 90 ing member 20, of spring metal or the like, the said member being substantially right angular in cross section as shown in Fig. 2, of the drawings. The member 20, comprises the two adjacent side portions 21 and 22, which are disposed at right angles to each other, the free edges of which side portions are bent inwardly at right angles to form the flanges 23 and 24. The side portion 21, is provided with an inwardly extending ear or 100 lug 25, at each end thereof, the said ear or lug being formed by slitting the side portion 21, a short distance along its length, near each edge thereof and then bending the portion between said slits to form the inwardly ex- 105 tending ear or lug 25.

The shape and size of the member 20 is such as to be adapted to snap over the projecting portion 12 and to be held thereon by the resiliency of the clasp- 110 ing member. When in operative position on the door frame, the member 20, is adapted to engage a portion of the inner corner of the door-jamb as shown in Figures 1, and 2, of the drawings. The edge or flange 23, of the member 20, is adapted to engage or rest against the farthest edge of one of the reinforcing plates or lugs 12, the inwardly extending ears 25 are adapted to engage the top and bottom edges of said plate 12, while the side portion 21, of the member 20, is adapted to cover the front face of said plate 12, and the side portion 22, and the flange 24, are adapted to engage the side and edge portions of the innermost portion or step of the door-jamb, as shown in Fig. 2. 120 125

In operation, when the vault door is in open position, in which position it is usually kept during banking hours, the clasp- 130 ing member 20, is slipped over one of the plates 12, in the following manner: The edge 24 of

the member 20, is placed flat against the edge of the innermost step of the door-jamb, and the member 20 is then swung around until the edge or flange 23, snaps over the farthest edge of the plate 12. The inwardly extending lugs or flanges 25, engaging the top and bottom edges of the said plate 12. As will be understood, the member 20, is adapted to open up about the corner formed by the two side portions 21 and 22, said corner acting as a hinge for permitting the giving way of said side portions a sufficient amount to allow the flange 23 to snap over the farthest edge of the plate 12, the resiliency of the metal will hold the same in place after it has been snapped on. The flanges 25, prevent the up and down movement of the member 20.

Obviously, the height and shape or size of the member 20, is determined by the size and shape of the lug or plate 12, and the size and shape of the innermost step of the door frame jamb. When the clasping member is in position on the door frame it will be noted that it will be impossible to fully close the door and lock the same, the said member 20, not only preventing a full closure of the door but also preventing the projection of the bolts 7, when the door is moved to a near closing position, as shown clearly in Figure 2, of the drawings.

It will be further noted that the member 20, is made of a material which will closely resemble in appearance the material of the door-jamb so as not to be noticeable thereon, thus avoiding the possibility of some one not aware of the presence of the device removing the same. Obviously, if desired a plurality of these members 20 may be positioned at several points along the opening in the door frame. In practice, the members 20, are placed in operative position along the door jamb, when the vault is opened in the morning, and are left in this position until removed by a person authorized to do so for closing and locking the vault door, at the close of business.

The objects of the invention are accomplished in a very simple manner by the construction shown and described, but it is considered that the same is capable of many alternatives without departing from the spirit of the invention as defined in the following claims.

What I claim and desire to secure by Letters Patent of the United States, is:-

1. In a vault, the combination with a door frame having a door-jamb, and a door adapted to be fitted therein; of means adapted for clasping a portion of said door jamb for preventing the full closing of the said door.

2. In a vault, the combination with a door frame having projections on the inner face thereof, and a door for said door frame; of a member adapted to be detachably clasped on one of said projections for preventing the closing of said door.

3. In a vault, the combination with a door frame having a projection on the inner face thereof, a door jamb, and a door adapted to be fitted in said door-jamb; of a member adapted to be detachably secured to said projection and engage a portion of said door-jamb for preventing the closing and locking of said door.

4. In a vault, the combination with a door frame having a projection on the inner face thereof and a door-jamb, and a door adapted to be fitted in said door-jamb; of a clasping member adapted to be detachably secured to a portion of said door frame for preventing the closing of said door, said member comprising a pair of side portions at right angles to each other, and an inwardly extending lug formed on one of said side portions near one end thereof, for engaging said projec. 85

5. In a vault, the combination with a door frame having a projection on the inner face thereof and a door-jamb, and a door adapted to be fitted therein; of a clasping member adapted for detachable engagement with said door frame for preventing the closing of said door, said member comprising a pair of side portions disposed at right angles to each other, one of said side portions having a 95 flange formed at the free edge thereof for engaging one edge of said projection, and the other of said side portions having an inwardly extending lug formed at one end thereof for engaging another edge of said projection.

6. In a vault, the combination with a door frame having a projection thereon on the inner face thereof and a door-jamb, and a door adapted to be fitted therein; of a clasping member adapted to be detachably secured to said door frame for preventing the closing of said door, said member comprising a pair of side portions disposed at right angles to each other, an inwardly extending flange formed at the free edge of each of said side portions for engagement with said door frame, and an inwardly extending ear formed on one of said side portions near each end thereof for engagement with the top and bottom edges of said projection.

In testimony whereof, I affix my signature, this 22nd day of November, 1927.

ALFRED H. JOHNSEN.
